Primary Examiner — Cynthia M Chin*(74) Attorney, Agent, or Firm* — Benesch, Friedlander, Coplan & Aronoff, LLP**CLAIM**

The ornamental design for a personal enclosure, as shown and described.

DESCRIPTION

FIG. 1 is a perspective view of a personal enclosure;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown within the frame and top of the personal enclosure represent stitching which forms a part of the claim. All other broken lines represent the environment in which the article resides and form no part of the claimed design.
